UNITED STATES PATENT OFFICE.

GEORGE W. ARCHER, OF ROCHESTER, NEW YORK, ASSIGNOR TO THE ARCHER MANUFACTURING COMPANY, OF SAME PLACE.

BARBER'S CHAIR.

SPECIFICATION forming part of Letters Patent No. 476,774, dated June 14, 1892.

Application filed March 9, 1892. Serial No. 424,321. (No model.)

To all whom it may concern:

Be it known that I, GEORGE W. ARCHER, of Rochester, in the county of Monroe and State of New York, have invented certain new and useful Improvements in Barbers' Chairs; and I do hereby declare the following to be a full, clear, and exact description of the same, reference being had to the accompanying drawings, forming a part of this specification, and to the reference-numerals marked thereon.

My present invention relates to that class of chairs especially adapted for barbers' use, and has for its object to improve their construction, whereby an adjustment necessary to place the occupant in the most comfortable position may be readily accomplished by the operation of a single part, and also the chair may be raised and lowered to suit operators of various heights; and to these and other ends the invention consists in certain novelties of construction and combinations of parts, all as will be hereinafter fully described, and the novel features pointed out in the claims at the end of this specification.

In the accompanying drawings, Figure 1 is a longitudinal section of a chair, showing my invention applied thereto; Fig. 2, a plan view of the seat-frame; Fig. 3, a vertical section taken on the line xx of Fig. 2. Fig. 4 is a sectional view taken on the line yy of Fig. 2. Figs. 5 and 6 are sectional views on the lines ab and cd , respectively.

Similar reference-numerals in the several figures indicate similar parts.

The back 1, seat-frame 2, depending bars 3, constituting part of the forward frame supporting the foot-rest, and arms 4 are of the ordinary or any preferred construction, the back being pivoted to the frame at 5 and to the rear ends of the arms at 6, the forward ends of the arms being pivoted at 7 to the depending front bars 3, which latter are pivoted to the frame 2 at 8, the construction being such that when the back is tilted to the rear the depending arms 3, carrying the foot-rest, are elevated.

The base 9, on which the chair is supported, is provided with suitable legs 10, and the connections between this base and the seat-frame

and adjusting mechanism form the subject-matter of my present invention.

Secured to the under side of the seat-frame 2 is a spider or frame composed of the side arms 11, rearwardly-extending arm 12, and forwardly-extending arm 13, said arms being preferably formed integral with the central annular portion or ring 14, provided on opposite sides with upwardly-projecting lugs 15 for steadyng the operation of the locking device, as will be described, and at the rear with lugs 16 for steadyng the movement of a longitudinally-sliding rack-bar 17, by which the adjustment of the chair is controlled. This bar 17 slides on the top of the spider and is prevented from lateral movement by the lugs 16 and also by depending lugs 18, with which it is provided, engaging the rear arm 12, and its forward end is also guided in its movements by a projection 19 on the spider, entering a groove 20 in its side. A link 21 is pivoted at one end to the forward portion of the rack-bar and at the other to the piece 50, connecting the depending bars 3, so that by the adjustment of the back the rack 17 is moved backward and forward and the adjustment of the chair will be accomplished.

Secured to the base 9, and preferably near its upper end, is a nut 22, in which operates the threaded standard 23, provided with an annular flange 24, to which is secured by rivets or otherwise a ring 25, provided with a series of perforations 26 near its periphery, and upon this ring the lower edge of the annular part 14 of the spider has its bearing, constituting a swiveled support for the chair, the parts being retained in operative connection by suitable bolts or screws 27 on the arms of the spider, which project beneath its edge, as shown, and prevent its upward movement, though they do not interfere with its being rotated thereon.

While I prefer to make the flange 24 and ring 25 separate, it is obvious they could be constructed in one piece, if desired.

On the inner sides of the standard are provided two projections 28, having vertically-extending slots, and located with the standard is a vertically-movable rod 29, having a

pin 30 co-operating with the slots in the projections or standard, and to the upper end of this rod is connected a device for engaging the bar 17 and locking it, consisting of a yoke 5 or casting 31, provided with a central aperture, through which the bar 17 passes, the laterally-extending sides projecting between the lugs 15 of the spider and the depending arm 32 projecting downward and adapted to engage one of the series of holes 26 in the plate 25, said arm being slightly longer than the portion of the yoke engaging the rack-bar 17. The connection between the rod 29 and the casting 31 is formed by extending the 10 rod through the lower portion of the casting and providing pins 33, engaging it on the upper and lower sides, as shown, so that the vertical movement of the rod will cause the lifting of the yoke 31; but the latter, which 15 is laterally rigid with the chair-seat, may turn independently of said rod. The lower end of the rod 29 is provided with a screw-thread of the same pitch as the thread in the nut 22 in the standard, and screwing upon it is a nut 25 34, pivoted on the end of the link 35, which in turn is pivotally supported on a foot-lever 36, pivoted to the chair-base and extending outward in position to be conveniently actuated by the operator. A spring 37 encircles the rod 29, 20 engaging at its upper end a washer 38 beneath the lugs 28, and its lower end is supported upon a washer arranged above a pin 39, passing through the rod above the nut, said spring holding the rod and the locking-yoke moved 25 downward in engagement with the rack-bar 17 and holding the projection 32 of the yoke in engagement with one of the perforations in the plate 25. In normal position the standard is held locked to the base by means of a 30 set-screw 40, passing through the side of the nut 22 and engaging the standard, and the tilting of the chair-back and foot-rest can be accomplished by the operator pressing on the end of lever 36, and through the link, nut, 35 and rod raising the yoke 31 a distance sufficient to release the rack 17, when by manipulating the back the desired adjustment can be secured, and if it is desired to rotate the chair-seat on the standard a further upward movement of the yoke will disengage the projection 32 from the plate 25, when the chair-seat and spider may be rotated on the latter plate to the desired position, the yoke moving with them independently of the rod, and upon the 40 release of the treadle the parts will become locked in position again by means of the action of the spring.

Should it be desirable to change the elevation of the chair to suit operators of different 45 heights, it is only necessary to loosen the set-screw 40, and the standard may be rotated in the nut 22 in the base and the chair-seat elevated or depressed. As the rod 29 rotates with the standard it will be moved upward 50 through the nut 34 without affecting the position

of the lever 36, and the connection formed by this nut between the actuating-lever and the locking-yoke or equivalent device is very desirable, as it enables me to employ a stationary releasing-lever connected 70 with a vertically-movable standard in such manner that the latter can be adjusted without affecting the position or operation of the former. When the desired vertical adjustment of the standard is accomplished, it may 75 be locked to the base again and the tilting and rotary movements of the chair governed by means of the foot-lever, as before described.

It is obvious that substantially the same mechanism as herein shown and described 80 could be employed in chairs in which the front is not adjustable, but the back only, the latter being connected to the rack-bar 17, said rack or an equivalent movable portion being, considered broadly, a movable part 85 governing the movement of the adjustable part of the chair.

While I prefer to employ all the adjustments herein described in my chair, it is obvious that the movable locking portion described as the yoke could be employed only to control the chair when moved on the standard or only when the back is adjusted, or both, as shown. Again, the same extensible connection between the lever and the part called 95 the "yoke" could well be employed in chairs having other adjustments—as, for instance, one in which the movement of a part corresponding in position only to the yoke would cause other adjustments or operations.

Instead of supporting the nut 34 on the lever, it is obvious that a screw could be connected to the lever and the nut formed on the rod 29.

Other similar modifications could readily 105 be made without departing from the spirit of my invention.

I claim as my invention—

1. The combination, with the supporting standard, an adjustable chair swiveled thereon, and a movable bar controlling its adjustment, of a movable locking projection on the chair engaging said bar and a vertically-movable rod on the standard swiveled to the locking projection, substantially as described.

2. The combination, with the supporting standard, an adjustable chair swiveled thereon, and a movable bar controlling its adjustment, of a movable locking projection on the chair engaging said bar and also the standard 115 for preventing movement on the latter, and a vertically-movable rod on the standard swiveled to the locking projection, substantially as described.

3. The combination, with the supporting standard, an adjustable chair swiveled thereon, and a movable bar controlling its adjustment, of the movable locking projection on the chair engaging said bar, a vertically-movable rod on the standard connected to the projec- 125 130

tion through a swivel connection, and a foot-lever connected to said rod, substantially as described.

4. The combination, with the supporting-standard, an adjustable chair swiveled thereon, and a movable bar controlling its adjustment, of a movable locking projection on the chair engaging said bar, a movable rod on the standard operating said projection, a base or support in which the standard is vertically adjustable, a lever pivoted on said base, and an extensible connection, substantially as described, between said lever and rod, whereby the chair may be adjusted and moved vertically and the locking device operated by means of the lever, as set forth.

5. The combination, with the supporting-standard, an adjustable chair swiveled thereon, and a movable bar controlling its adjustment, of a movable locking projection on the chair engaging said bar, and also the standard, for preventing movement on the latter, a movable rod on the standard operating said projection, a base or support in which the standard is vertically adjustable, a lever pivoted on said base, and an extensible connection, substantially as described, between the rod and lever, whereby the chair may be turned, adjusted, and moved vertically, and the locking device operated by the lever, as set forth.

6. The combination, with the stationary base, the standard vertically adjustable thereon, and the chair swiveled on the standard, of a locking device for preventing the movement of the chair on the standard, an operating-lever on the base, and a swiveled extensible connection, substantially as described, between the lever and locking device, whereby the chair may be turned, the standard adjusted vertically, and the locking device operated by means of the lever, as set forth.

7. The combination, with the standard, a chair swiveled thereon, of a vertically-movable projection for locking the chair to the standard, the rod for actuating the projection, a stationary foot-lever for actuating the rod, and a swivel connection between the lever and locking projection, whereby the latter may be actuated irrespective of the lateral adjustments of the chair, substantially as described.

8. The combination, with the stationary base, the vertically-adjustable standard, and an adjustable chair mounted thereon, of a locking projection controlling the adjustments of the chair, a foot-lever mounted on the base, and an extensible connection, substantially as described, between the projection and lever, whereby the former may be actuated by the latter irrespective of the vertical adjustment of the standard, as set forth.

9. The combination, with the stationary base, the vertically-adjustable standard, and a chair swiveled on the standard, of a locking projection for securing the chair to the standard, a foot-lever mounted on the base, and an

extensible connection, substantially as described, between the foot-lever and locking projection, whereby the latter may be actuated by the former irrespective of the vertical adjustment of the standard, as set forth.

10. The combination, with the stationary base, the vertically-adjustable standard, and an adjustable chair swiveled thereon, of a securing device controlling the adjustment and rotary movement of the chair, a foot-lever mounted on the base, and an extensible connection, substantially as described, between the foot-lever and securing device, whereby the latter may be actuated by the former irrespective of the vertical adjustment of the standard, as set forth.

11. The combination, with a standard, an adjustable chair swiveled thereon, and a movable rack controlling its movement, of the yoke engaging the bar, vertically movable on the chair, the rod swiveled to the yoke and prevented from rotation on the standard, the spring engaging the rod and standard for holding the yoke in engagement, and a foot-lever connected to the rod for actuating it, substantially as described.

12. The combination, with the stationary base having the nut, the threaded standard operating therein, and the chair mounted on the standard, of a locking device for controlling the movements of the chair, a foot-lever on the base, and connections between it and the locking device, embodying a nut and screw, having the pitch of the thread on the standard, substantially as described.

13. The combination, with the stationary base having the nut, the threaded standard operating therein, and the adjustable chair mounted on the standard, having the movable bar, of the yoke, the threaded rod swiveled to the yoke, the slot-and-pin connection between the standard and rod, the spring for actuating the yoke, the nut on the rod, and the lever to which said nut is connected, substantially as described.

14. The combination, with the stationary base having the nut, the threaded standard operating therein, and the adjustable chair swiveled on the standard, having the movable bar, of the yoke engaging the bar and the standard, the threaded rod swiveled to the yoke, the slot-and-pin connection between the rod and standard, the spring for actuating the yoke, the nut on the rod, and the lever to which said nut is connected, substantially as described.

15. The combination, with the hollow standard having the perforated ring at its upper end, of the seat-frame, the spider secured thereto having the annular portion 14, the adjustable chair-back and depending bars connected by the arms, the sliding rack-bar connected to the depending bars, the yoke 31, having the arm 32, the rod 29, swiveled to the yoke, and a foot-lever for operating it, substantially as described.

16. The combination, with the base, the

standard screwing therein, having the ring, of the seat-frame, the spider having the annular portion 14 and lugs 15 thereon, the rack-bar 17, the adjustable chair connected thereto, the threaded rod swiveled to the yoke, the spring for retracting it, the nut screwing on the rod, the lever pivoted on the

base, and the link pivoted to the lever and nut, substantially as described.

GEO. W. ARCHER.
